UNITED STATES PATENT OFFICE.

EMMETT BLEVENS, OF LOUISVILLE, KENTUCKY, ASSIGNOR TO THE EMMETT BLEVENS COMPANY, OF LOUISVILLE, KENTUCKY, A CORPORATION OF KENTUCKY.

COMBINED STOCKING AND PAD FOR ARTIFICIAL LEGS.

1,319,637.

Specification of Letters Patent.

Patented Oct. 21, 1919.

Application filed October 28, 1918. Serial No. 259,999.

To all whom it may concern:

Be it known that I, EMMETT BLEVENS, a citizen of the United States, residing at Louisville, in the county of Jefferson and State of Kentucky, have invented certain new and useful Improvements in Combined Stockings and Pads for Artificial Legs; and I do declare the following to be a full, clear, and exact description of the invention, such as will enable others skilled in the art to which it appertains to make and use the same.

This invention relates to bearings for the stumps of amputated legs, and it relates more particularly to a combined stocking and pad for use in fitting the stump in the socket of an artificial leg.

One of the objects of this invention is to minimize as far as practicable any pressure upon the portion of the stump of the leg adjacent to its end, and thus avoid discomfort and danger of swelling, such as frequently results when such pressure is permitted.

Another object is to provide a pad which is gradually thickened from its bottom portion upward, in order to compensate for the shrinkage of the leg stump and thus increase the comfort of the wearer.

Another object is to provide a device of this character which is simple of construction and may be manufactured at a comparatively low cost.

Reference is had to the accompanying drawings in which like parts are indicated by similar reference symbols throughout the several views.

Figure 1 is a side elevation of a leg stump having the inner sock of my improved bearing thereon, the outer sock being shown as collapsed about the lower portion of the leg stump, the elastic pad being omitted, and parts being broken away.

Fig. 2 is a view somewhat similar to Fig. 1, with the elastic pad in place, parts being shown as broken away, and the lower part of the stump-socks being shown in vertical section.

Fig. 3 is a sectional view corresponding to Figs. 1 and 2, but shows all the parts in proper relation, an artificial foot and leg being indicated in dotted lines.

Fig. 4 shows a transverse section of the device along the line 4—4 of Fig. 3.

Fig. 5 is a view somewhat similar to Fig. 4, illustrating the relation of the same elements fitting upon a leg-stump of somewhat smaller circumference.

Fig. 6 is a side elevation of the elastic pad extended.

Fig. 7 is a sectional view along the line 7—7 of Fig. 6.

Fig. 8 shows a section along the line 8—8 of Fig. 6; and

Fig. 9 is a fragmental view, partly in vertical section, of a somewhat modified form of the invention, showing an increased number of thicknesses in the leg of the sock.

The inner stump-sock is in the form of a tapering bag closed at the small end 13 and open at the upper end, and is indicated by the numeral 10; the outer stump-sock 11 being secured to or made integral with the inner stump-sock at 12. Preferably, the junction 12 is formed by interweaving or inter-knitting the lower end of the outer sock to a portion of the inner sock at a slight distance above the lower closed end 13 of the latter. The distance from the junction 12 to the lower end may be from one to several inches; but the distance should not exceed that which is necessary to allow perfect freedom of the end of the stump; that is, the comparatively tender and sensitive portion of the stump should not be touched by any part of the bearing except the single thickness of woven or knitted fabric which constitutes the lower end portion 13 of the inner sock.

The outer sock and the major portion of the inner sock combine to form a pad which is thicker than the portion 13, and this tends to provide a space between said portion 13 and the inner wall of the artificial leg. However, the space or pressure relief thus provided is usually inadequate; and moreover, the bearing thus provided by the inner and outer socks has not sufficient rigidity or solidity to obtain the best results when the usual fastening strap or clamp is secured thereon for attaching the artificial leg to the bearing. Therefore, the pad 14 is provided.

This pad is shown in detail and detached

in Figs. 6, 7 and 8, and is shown applied in Figs. 2, 3, 4 and 5. It is preferably constructed of a sheet of sponge-rubber having its edges formed with a wide bevel. When the pad is applied to the stump, two of these bevel edges may meet or approximately meet as illustrated in Fig. 4, or they may be lapped upon one another as illustrated in Fig. 5, so that this pad forms an elastic bearing interposed between the sock legs.

The inner and outer socks, being of elastic material such as woven or knitted fabric, will readily conform to leg-stumps of different sizes, and the elastic pads 14 may be made of different sizes, so that the proper size may be selected for fitting any particular size or shape of leg. When the proper size has been selected and placed around the inner sock, and the stump inclosed therein, as shown in Fig. 2, the outer sock 11 is drawn up over or around the elastic pad 14, and thus holds the elastic pad in its position around the stump.

When the artificial leg is placed over the leg-stump, as shown in Fig. 1, its upper portion embraces the pad or bearing which is formed by the several thicknesses of material of the inner and outer socks and the intermediate pad, so that the lower end of the stump is disposed concentric with the shell or socket of the artificial leg; or, in other words, there is an air space surrounding the lower lower end portion of the inner stump-sock.

The pad 14 is preferably formed with beveled edges 15 and 16 which wholly or partly overlap one another, with the lower edge 17, the upper edge 18 substantially parallel to the lower, and oblique edges 19 and 20.

The upper edge 18 preferably extends to the knee-cap, which prevents the pad from working upward, while the oblique edges 19 and 20 preferably diverge upwardly to allow freedom of action of the leg muscles back of the knee.

Although I have shown the upper and lower edges 17 and 18 curved, which is the preferable shape, this is not an essential feature. Moreover, although sponge-rubber with smooth faces is the preferable material for forming the pads 14, my invention is not restricted to the use of sponge-rubber, as other suitable elastic material may be used as desired.

It often occurs that the leg-stump shrinks to a size considerably less than the original size, and in order that it may be artificially restored to approximately its former size, and at the same time provide an extra thick padding to compensate for the absence of flesh upon the bones and sinews of the stump, I may provide one or more additional 60 stump sock legs, as illustrated at 10' and

11' in Fig. 9, but with a single covering only over the end of the stump. In such case the elastic pad 14 may either be dispensed with, or placed between the inner sock and one of the intermediate socks, or between two intermediate socks, or between one of the intermediate socks and the outer sock.

I claim as my invention:

1. A stump-leg-bearing comprising an inner stump-sock having a closed lower end, an outer stump-sock having an open lower end, the inner and outer stump-socks being joined together at the extreme lower end of the latter, the junction of said inner and outer socks being at a slight distance above the closed lower end of the inner sock, and a sheet of elastic material removably mounted between the legs of said outer and inner socks, substantially as described. 85

2. A stump-leg-bearing comprising an inner stump-sock having a closed lower end, an outer stump-sock having an open lower end, the inner and outer stump-socks being joined together at the extreme lower end 90 of the latter, the junction of said inner and outer socks being at a slight distance above the closed lower end of the inner sock, and a sheet of sponge-rubber removably mounted between the legs of said outer and inner 95 socks, substantially as described.

3. A stump-leg-bearing comprising an inner stump-sock having a closed lower end, an outer stump-sock having an open lower end, the inner and outer stump-socks being 100 joined together at the extreme lower end of the latter, the junction of said inner and outer socks being at a slight distance above the lower end of the inner sock, and a sheet of sponge-rubber having beveled 105 edges removably mounted between the outer and inner socks and surrounding the latter and having two of its beveled edges lapped upon one another, substantially as described.

4. A surgical appliance adapted for use 110 in a bearing for supporting amputated leg stumps in artificial legs, comprising an inner sock in the form of a tapering bag of elastic fabric closed at its small end and open at its upper end, the small end being adapted 115 to fit over the end of the stump, and the large end to be drawn over the knee of the wearer, and one or more sock legs open at the top and secured at the bottom to said inner sock above the closed end thereof, whereby a single thickness is provided to go over the sensitive portion of the stump of the wearer, and a padding effect is secured at the bearing portion of the appliance, substantially as described. 125

5. A surgical appliance adapted for use in a bearing for supporting amputated leg stumps in artificial legs, comprising an oblong sheet of sponge rubber having smooth inner and outer faces, and beveled edges, the 130

upper and lower edges being substantially parallel, and the end beveled edges being adapted to overlap to form a smooth continuous band around the stump of the wearer, and the upper edges being cut away at the corners to leave clearance for the muscles behind the knee of the wearer, with

means for holding said pad in place on the stump of the wearer, substantially as described.

In testimony whereof I have hereunto set my hand.

EMMETT BLEVENS.
